UNITED STATES PATENT OFFICE.

PETER LUDWIG, OF CHICAGO, ILLINOIS.

STEAM-PUMP.

SPECIFICATION forming part of Letters Patent No. 630,812, dated August 8, 1899.

Application filed March 5, 1898. Serial No. 672,624. (No model.)

To all whom it may concern:

Be it known that I, PETER LUDWIG, a citizen of the United States, residing at Chicago, in the county of Cook and State of Illinois, 5 have invented a new Steam-Pump in conjunction with a new Valve-Gear and other new Features, of which the following is a specification.

My invention relates to improvements in duplex steam-pumps in which both sides of the pump may be operated in connection with each other by the intermediate valve-gear, or either of the two sides may be cut out entirely and only one side operated, or each side may 15 be worked independent of the other under different piston speeds, pumping different liquids. By the arrangement made in the exhaust connection the pump may be worked as "condensing" without using an additional 20 vacuum or circulating pump. I attain such objects by the mechanism illustrated in the accompanying drawings, in which—

Figure 1 is a side elevation of the pump. Fig. 2 is a front elevation of the pump; Figs. 25 3 and 4, a front and side view of the piston-rod clamp with guide-block; Figs. 5 and 6, a front and side view of the end pieces for the connecting-rods; Figs. 7 and 8, a plan and sectional view of the pump-piston; Fig. 9, a 30 front view of the stuffing-box with handles; Fig. 10, a side elevation of the gland with screwed end; Fig. 11, a cross-section of a gland with flanged end; Fig. 12, a plan view of same; Fig. 13, a detailed view of the wrist-bar; Fig. 35 14, a cross-section of the pump; Fig. 15, a longitudinal sectional elevation of the pump along the axis of the piston-chambers.

Similar letters of reference indicate like parts in the several views.

40 The steam-cylinder casing *a*, the exhaust-chamber *b*, the latter serving as a standard or leg, the pump-cylinder casing *c*, with the air-chambers *d* and *e*, and the suction-chamber *f* constitute, in conjunction with the center pieces *g* and *h*, the framework of the pump.

45 The pump in its general features is the same as any other pump, but differs from the pumps now in use in so far as two different liquids may be pumped at the same time under different piston speeds and either one or both sides may be worked condensing without the attachment of a vacuum or circulating pump.

The steam-cylinders are provided with the "Corliss" type of valves; but instead of having the connecting-rods of the valve-crank 55 connected to a wrist-plate they are connected to the rocking bars *i* and *k* on both sides of the cylinder-casing. Said rocking bars *i* and *k* are connected to the bent levers *m* and *n* by the rods *o* and *p*. The bent levers *m* and *n* are fastened to the rocking shafts *q* and *r*. To the latter the rocker-arms *s* and *t* are also fastened. The rocker-arms *s* and *t* consist of a center piece and two side pieces or slides, the latter being adjustable in order to take 65 up the wear of the blocks *u* and *u'*. A detailed view of one of these guide-blocks, with the clamps *v* and the bolts *w*, is shown in Figs. 3 and 4. These clamps *v* and *w* are fastened to the piston-rods *x* and *y*. 70

The reciprocating motion of the piston-rods *x* and *y* is transformed to a rocking motion of the rocker-arms *s* and *t*, as can be readily seen. From there the motion is transmitted to the valves by the bent levers *m* and *n*, the 75 rods *o* and *p*, and the rocking bars *i* and *k*.

The connecting-rods *o* and *p* are provided on their ends with pieces *z*, *a'*, *b'*, and *c'*, the latter having a slot to hook them to the corresponding bolts. This arrangement is made 80 for the purpose of allowing the pump to be changed rapidly from duplex to single, or vice versa.

The standard *d'* serves as bearing for the rocker-shafts *q* and *r* and is fastened to the 85 center pieces *g* and *h*.

The above is a general description of the pump working duplex. In order to work each side of the pump independent from the other, the rods *o* and *p* have to be unhooked from 90 the bent levers *m* and *n* and the upper ends of the rocking bars *i* and *k* and hooked into the bolts of the guide-blocks *u* and *u'* and the bolts in the lower end of the rocking bars *i* and *k*. This connection is indicated by the 95 dotted lines in Figs. 1 and 2. After the valve-gear has undergone the above alteration in the connections either side, or both, may be used as single pumps, and, if desirable, two different liquids may be lifted and discharged 100 at the same time and at different piston speed. The steam for the cylinders is supplied by the pipes *e'* and *f'*. The exhaust is carried away to the atmosphere by the pipes *g'* and *h'*, or

where circumstances allow it the exhaust-steam may be led into the suction-chamber f by the pipes i' and h' , so that the steam coming in contact with the cold water will condense and create a vacuum behind the piston. The valves l' , m' , n' , and o' are the means to change the pumps from condensing to non-condensing, or vice versa. The exhaust-pipes i' and h' , shown in the drawings in a straight run, may be cross-connected, so that either one or both cylinders may exhaust into one or both suction-chambers.

In the present improvement the exhaust-pipe sections i' and h' are made separate and detachable from the body of the pump, and to this end the respective valves l' , m' , n' , and o' are arranged in the body portion of the pump in manner indicated in Fig. 15, so as to control communication with such exhaust-pipe sections, so that when said valves are closed the said pipe-sections can be detached without affecting in the least the action of the pump in a non-condensing manner, as heretofore described. The inlet for the suction is through the opening p' and q' in the two sides and r' and s' in front of the suction-chamber. t' and v' are hand-holes in the suction-chamber f for the purpose of getting access to the inside of said chamber in order to remove the sand, &c., which may accumulate, so that the base f serves also the purposes of a mud-catcher.

The discharge from the pump-cylinder is through the openings w' and x' on both sides of the pump-cylinder casing.

The steam-cylinder casing a , the pump-cylinder casing c , and the air-chamber f , with the exhaust-chamber b , are provided in the middle with partitions, so that each side is entirely independent from the other.

The piston for the pump, as shown in Figs. 7 and 8, consists of the piston-head y' , secured firmly to the piston-rod, the follower-head z' , loosely fitted to the rod, and the elastic packing a^2 . Said parts y' , z' , and a^2 are held together by four bolts. By tightening these four bolts the elastic packing will be pressed together, and consequently increase its diameter. In order to set the elastic packing, it is necessary to remove the cylinder-head only.

The gland, as shown in Figs. 9, 10, 11, and 12 in different views, is used all over the pump wherever a gland is necessary, and the same may be applied on any similar piece of machinery wherever needed. The stuffing-box proper, b^2 , screws into the casing c^2 instead of screwing over the outside of same. The metallic ring f^2 will prevent the stuffing-box from cutting into the packing when the latter is screwed in. Said stuffing-box b^2 is provided with handles d^2 , as shown in Figs. 9 and 10, and obviates the use of a wrench. The casting c^2 may be made with screwed end, Fig. 10, or with flanged end, as shown in Figs. 11 and 12.

I am aware that prior to my invention duplex pumps have been constructed so that one

side only could be set working. I am also aware that prior to my invention steam-pumps have had their exhaust-steam passage of the steam-cylinder connected to the outlet-passage of the water-cylinder. I therefore make no claim broadly to such feature of construction; but,

Having thus fully described my said invention, what I claim as new, and desire to secure by Letters Patent, is—

1. In a duplex steam-pump, the combination with a pair of cylinders, their series of rocking valves, and the actuating mechanisms therefor, of a pair of rocking bars common to the series of valves, and provided with upper and lower wrist-pins or bolts, a pair of rocking levers actuated by the piston-rod, and provided with corresponding upper and lower wrist-pins or bolts, and a pair of connecting-rods adapted to engage either the upper or lower set of wrist-pins or bolts, to change the operation of the pump from a normal duplex into a separate and independent action, substantially as set forth.

2. In a valve mechanism for duplex steam-pumps, substantially as herein described, the combination of steam-cylinders, steam-chests, steam-valves, valve-actuating mechanisms, a pair of valve-operating bars provided with upper and lower wrist-pins or bolts, a pair of piston-actuated levers provided with corresponding upper and lower wrist-pins or bolts, and a pair of connecting-rods adapted to engage either the upper or lower set of wrist-pins or bolts, substantially as set forth.

3. In a valve mechanism for duplex steam-pumps, as herein described, the combination of steam-cylinders, steam-chests, steam-valves, valve-actuating mechanisms, a pair of valve-operating bars provided with upper and lower wrist-pins or bolts, a pair of piston-actuated levers provided with corresponding upper and lower wrist-pins or bolts, and a pair of connecting-rods formed with hook-shaped ends and adapted to engage either the upper or lower set of wrist-pins or bolts, substantially as set forth.

4. In a valve mechanism for duplex steam-pumps, substantially as herein described, the combination of steam-cylinders, steam-chests, steam-valves, valve-actuating mechanisms, a guide-block carried by the piston-rod, and a rocking arm of the valve mechanism provided with adjustable side pieces or slides, that engage said guide-block, substantially as set forth.

5. In a valve mechanism for duplex steam-pumps, substantially as herein described, the combination of steam-cylinders, steam-chests, steam-valves, the series of valve-stems and connecting-links, and a rocking bar common to said valve connections, and formed by a central hub and oppositely-extending members bolted separately to said hub, substantially as set forth.

6. In a steam-pump, substantially as herein described, the combination of the steam-cyl-

inder provided with an individual controlling-valve in its exhaust-passage, the suction-chamber of the pump-cylinder provided with an individual valve controlling a passage 5 therefrom, and a pipe connection between said passages secured detachably in place, substantially as set forth.

7. In a duplex steam-pump, substantially as herein described, the combination of the 10 duplex steam-cylinders provided with indi-

vidual controlling-valves in their exhaust-passages, the suction-chambers of the duplex pump-cylinders provided with individual pipe connections between said passages secured detachably in place, substantially as 15 set forth.

PETER LUDWIG.
